F. J. LITTELL MACHINE CO., OF CHICAGO, ILLINOIS, A CORPORATION OF ILLINOIS

MEANS FOR FEEDING RIVETS OF SPECIAL SECTION TO RIVET PRESSES

Application filed November 7, 1928. Serial No. 317,859.

This invention relates to rivet presses or punch presses equipped with means for automatically delivering into the path of the plunger the rivets having a section especially designed to assume a definite position in a structural member, and has for its object to provide means whereby such special rivets, delivered en masse to a hopper, will be caused to issue from the hopper in a particular position, passed in said position to a positioning slide by which they are spotted in the place of use, and thereby retained until assembled with the structural member in readiness to be secured therein by the descent of the press plunger.

Another object is to provide means whereby rivets, feeding from a container where they are confined en masse, are made to assume positions en train with their characteristic profiles at a predetermined angle of horizontal rotation, to which end, another feature of the invention consists in providing the container with a rotary selector, subdivided into radial spaces proportioned to receive the rivets only when they are in the predetermined position, and preventing the entrance of rivets not in such position.

Another object is to provide automatically releasing drive means for such a feeder and one in which the drive of the feed, in case a rivet assumes a position across the dividing plane between the stationary and rotating parts of the feeder, will yield under the choking of the rotary member to avoid breakage, and the rotary member will receive a slight retrograde movement sufficient to release the gripped rivet and permit the rivet to continue its movement toward the place of use and out of obstructing position.

In the accompanying drawings, in which the preferred embodiment of the invention is shown by way of illustration—

Figure 1 is a side elevation of the principal operation of a riveting press in which the invention is embodied.

Figure 2 is a view similar to Figure 1 but on an enlarged scale and with omission of the rivet-supplying means and the driving mechanism of the press.

Figure 3 is a front view of parts shown in Figure 2.

Figure 4 is a plan view of parts shown in Figures 2 and 3, portions above the plane of the work table being omitted.

Figure 5 is a top plan view, and Figure 6 an axial section on line 6a—6a in Figure 5 of the rivet container and feeding means, which figures are on an enlarged scale;

Figure 7 is a detail sectional view on line 7a—7a in Figure 5 of the forward and retrograde driving ratchet employed for operating the rivet supply;

Figure 8 is a detail view showing the association of the chute with the rivet container; and

Figure 9 is a detail sectional view taken on line 9—9 of Figure 8.

1 represents a bed; 2 a work table; 3 a rivet supply chute; 4 a hopper for feeding rivets to said chute; 5 a riveting die; 6 a press plunger; 7 a main shaft; 8 the fly-wheel of the press, and 9 the hopper base in a riveting press, which parts, so far as enumerated and except as hereinafter identified more in detail may follow known construction, or at least correspond in construction and operation with similar parts disclosed in our application, Serial No. 300,240, filed August 17, 1928.

Hopper base 9 is rotatably mounted so through means of shaft 10 in a bracket 11, and through means of an integral sector 12 having slot 13 and bolt 14, may be fixed with said base at an appropriate angle to the horizontal to cause the rivets in the hopper 4 to gravitate toward the discharge side of the hopper, as is also described in our copending application referred to.

Shaft 10 has mounted upon it a driving ratchet 15 and pawl 16 pivotally mounted on arm 17 that is oscillated through pitman 18 from crank 19 on shaft 20 which is constantly driven during the intermittent driving of the shaft 7. Thus the motor M through the shaft 25 and belt 24 rotates the pulley 23 which, in turn, through reduction gears 21, 21, rotates continuously the shaft 20. The fly-wheel 8 is driven constantly by the belt 26 which leads from the shaft 25; and the fly-wheel, by means of a suitable clutch mecha-

nism (not shown), imparts intermittent motion to the shaft 7, such intermittent motion being controlled by means of a foot treadle or other suitable device.

- 5 Ratchet 15, as may be seen from Figures 5 and 7, is composed of a plurality of plates spaced apart by means of an inserted washer, and comprises two sets of teeth, namely, teeth 27, having rearwardly presented faces 10 28 engaged by forward driving dog 29 to impart a forward step to the rotation of the ratchet and consequently to movable parts of the hopper 4 on each stroke of the crank 19 and teeth 30, having rearwardly presented faces 15 31 engaged by the dog 32 that is rigid with the pawl 16 imparting a slight retrograde movement to the ratchet at each stroke of said crank. Both the dog 32 and the dog 29 have pivotal action about the center 33 on the 20 outer end of the oscillating arm 17, dog 32 being held to its duty by means of spring 34, and the dog 29 being controlled by gravity. It is to be observed from an inspection of Figure 1 that the dog 32 is governed in its 25 movement by engagement with the pitman 18. Tooth faces 28 and 31 are at such circumferential distances apart on the periphery of the ratchet 15 that on the forward stroke of the pawl 16, dog 29 will impart a full forward 30 stroke of the ratchet and the parts which it drives commensurate with the throw of the oscillating arm 17; but the dog 32, which at the beginning of such movement is in engagement with a face 31, will by the engagement 35 of its lifting pin 35 with the rod 18 be given an upward movement on center 33 sufficient to release tooth 30, which is for the time being engaged by the dog 32, so that the end point of the forward drive under the dog 29, by 40 reason of the continued gravitation of said dog 29 into engagement with its tooth face 28, will be sufficient to put face 31 in advance of the dog 32; and then on the return movement of rod 18, dog 29 rides upon the incline of 45 the tooth with which it has been engaged until it drops behind the next ensuing face 28; but toward the end of the return stroke, dog 32 will have engaged the next ensuing face 31 and imparted a slight retrograde movement 50 to the ratchet sufficient to release any grip that may have occurred between the stationary and revolving members of the hopper to be described.

In addition to the features described, 55 ratchet 15 has a slip drive connection with the shaft 10 provided by any approved form of frictional clutch faces 36 (Figure 5), so that in case the rotating member within the hopper 4 becomes positively chocked by the 60 grip of a rivet between rotating and stationary parts, breakage will be avoided.

Referring now to Figures 5 and 6, 37 represents a spider rotating with a vertical shaft 38, which is driven by spiral gear 39a that is 65 keyed to the shaft, as shown. The gear 39a

is rotated by a second spiral gear 39 which is mounted upon the shaft 10. The spider carries agitators 40 within the hopper that keep the mass of rivets stirred up, and also carries the hopper wall 4, so that the hopper likewise rotates with the shaft 38. Shaft 38 is also made to rotate a selector 41 since the latter is rigidly connected with the bottom of the rotating hopper 4. The selector is equipped within its perimeter with radial partitions 42 that form pockets 43 that become filled with the rivets as the selector rotates, receiving the rivets however only in a definite position for the reason that each rivet X, as will be seen in Figure 5, has a flat face X' and the distance between the partitions is less than the full diameter of a rivet, so that no rivet can enter except it be at an angle of rotation which presents its minor diameter transversely of the pocket formed between 55 two partitions. By rotation of the selector 41, the rivets enter the chute 3, as shown, and will keep the chute filled so that a fresh rivet is presented at the lower end of the chute as fast as an antecedent rivet is used.

As shown in Figure 6, chute 3 is mounted at its upper end in the stationary base 9 of the hopper. If, in the feeding of the rivets, a rivet should come into the position shown in Figure 5, in which it crosses the plane between the rotating selector 41 and the non-rotating base 9, the frictional clutch 36 will yield and avoid breakage that would otherwise occur by the chocking of the selector, but since during the idling movement of the hopper drive, which would result from such slippage, the press will have used up another rivet, the column will have advanced to clear the obstruction and the feeding operation will be resumed as intended. In order to avoid gripping an obstructing rivet in the position referred to, the slight retrograde action in the ratchet 15 comes into play on each return stroke of the arm 17 as already described, and this slight picking up movement releases 110 the rivet.

In the lower end of the chute 3 the rivets are delivered into a slideway 44 in which is mounted the positioning slide 45 that spots the rivets, as shown at the point X'' in 115 Figure 4. In arriving in front of the positioning slide 45, each rivet has traveled with its flat face against one side of the chute 3, the chute being of less width than the major diameter of the rivets, and the rivets reach 120 the slideway with their flat faces presented toward the front of the machine, which is the position that they are desired to assume in their assembly with the structural member (indicated at Y in Figures 1 and 2). In order to prevent displacement of the rivets from this position of rotation in the interim between leaving the chute 3 and entering the slideway 44, a finger 46, shown in dotted lines in Figures 1 and 2 and in plan view in 125

Figure 4, is pivoted at 47 and stands normally vertical under influence of a spring 48 (Figure 3) which presents the upper end of the finger in position to engage the flat face of the rivet, as shown in Figures 1, 2, 3, and 4. When the positioning slide 45 occupies its rearward position, the finger 46 is disposed in the path of the rivet, as shown in Figure 2, and as the slide moves forward the finger advances in the direction of travel of the slide, being pushed by the rivet. To this end, the finger 46 forms one end of a bell crank lever of which the other arm, as shown at 50, is provided with a slot through which extends a vertically movable rod 49 having its upper extremity secured to the plunger 6. Compensating springs 51 and 52 may be provided at the bottom and top, respectively, of the rod 49, and the lower compensating spring 51 is adapted to engage the arm 50 of the bell crank lever and move that arm upwardly, and hence the arm 46 forwardly, upon downward movement of the plunger 6, at approximately the same rate of speed as the slide moves in advancing the rivet. Thus, during the early movement of the finger it is pushed by the rivet, but when about one half of the stroke has taken place, the spring 51 engages the arm 50 and drives the finger 46 slightly in advance of the rivet. As the rivet approaches the limit of its forward travel, the end of the finger 46 passes beneath the lower plane of the positioning slide and remains in a concealed position until the slide commences to recede, whereupon the rod 49 commences to descend and the finger 46 moves rearwardly independently of the slide and at approximately the same rate of speed until it finally comes to rest in the position shown in dotted lines in Figure 2. It will be understood that by means of such a provision, the finger 46 is positively controlled in its movement by means of the rod 49, and with the exception of the first part of its stroke forward, is advanced or retarded independently of the slide 45 or the rivet which is moved by the slide. The upper compensating spring 52 is confined to its portion of the shaft 49 by the nuts 53 and a part 54 secured to the plunger 6, which part abuts the lower end of the spring.

Inasmuch as the positioning carrier 45 is always at its forward limit whenever the plunger 6 is elevated, the rivet which it spots will be held in position while the structural member Y is being maneuvered to bring its prepared opening over the rivet; and during the riveting stroke when the positioning carrier recedes, the rivet, which is now engaged by the structural member with the flat face of the rivet against the offset in the structural member which necessitated the use of the special design of rivet, will be firmly held in position to receive the upsetting end of the riveting die 5.

After riveting is complete, the work is kicked out, preferably by means already described in connection with our copending application hereinbefore identified, and which consist generally of a pair of rods 55 normally depressed by springs 56, but adapted to be elevated into lifting engagement with the structural member Y on each upstroke of the press, for instance, through means of lever 57 pivoted at 58 and engaged by pick-up hook 59 which is drawn upward through means of rod 60 mounted at its upper end in bracket 61 on the plunger 6.

The means for imparting timed forward impulses to the positioning carrier 45 is likewise disclosed in our copending application and consists of bell crank lever 62 fulcrumed at 63, moved in the forward direction by spring 64 and in the rearward direction by cam 65 mounted on the plunger 6, and cooperating with the anti-friction roller 66 on the bell crank lever.

We claim:

1. In means for feeding rivets to a rivet press, a hopper having a discharge opening, a selector moving in said hopper to bring rivets to the discharge opening, and means moving said selector, normally having a retrograde movement in addition to a forward movement; the retrograde movement alternating definitely with the forward movement, but being materially less in amplitude than the forward movement.

2. In means for feeding rivets to a rivet press, a hopper having a discharge opening, a selector moving in said hopper to bring rivets to the discharge opening, and means for moving said selector, having a retrograde movement in addition to a forward movement; the driving means including a ratchet and two dogs, one of which acts forwardly on the ratchet and the other of which acts rearwardly thereon.

3. In means for feeding rivets to a rivet press, a hopper having a discharge opening, a selector moving in said hopper to bring rivets to the discharge opening, and means for moving said selector, having a retrograde movement in addition to a forward movement; the driving means including a ratchet and two dogs, one of which acts forwardly on the ratchet and the other of which acts rearwardly thereon; and means for holding out of action the rearwardly acting dog for a portion of its return stroke.

Signed at Chicago, Illinois, this 1st day of November, 1928.

RUDOLPH A. SKRIBA.
FREDERICK J. LITTELL.
